UNITED STATES PATENT OFFICE.

ROCCO VERDONE, OF NEW YORK, N. Y.

FIRE-EXTINGUISHER.

1,231,815.

Specification of Letters Patent.

Patented July 3, 1917.

Application filed October 31, 1916. Serial No. 128,657.

To all whom it may concern:

Be it known that I, ROCCO VERDONE, a subject of the King of Italy, and resident of New York city, borough of Manhattan, in the county of New York and State of New York, have invented certain new and useful Improvements in Fire-Extinguishers, of which the following is a specification.

My invention relates to improvements in fire extinguishers of the piston or plunger type, wherein the extinguishing material or liquid, such as a suitable chemical solution, is forced from the extinguisher by reason of the reciprocations of the piston or plunger. In such extinguishers, as known to me, the operating mechanism is usually made substantially the length of the inclosing casing that contains the extinguishing liquid, and where such extinguishers are made of sufficient length to contain a relatively large volume of such liquid, the piston tube or rod has been made correspondingly long, thereby entailing upon the operator the work of reciprocating the piston back and forth for a considerable distance, requiring longer movement of his arm than is convenient, so that it has been customary, as known to me, to make such extinguishers of relatively short length, to enable the operator to more readily operate the piston.

The object of my invention is to provide an extinguisher of the class referred to wherein the casing may be made relatively long to contain a relatively large amount of extinguishing material or liquid, and to provide therein an operating mechanism of a relatively short length, whereby the operator need reciprocate the piston for a relatively short or convenient length of stroke, and whereby substantially all of the contents of such relatively long casing may be discharged by the operation of the piston.

My invention comprises novel details of improvement and combinations of parts that will be more fully hereinafter set forth and then pointed out in the claim.

Reference is to be had to the accompanying drawings forming part hereof, wherein Figure 1 is a longitudinal sectional view of a fire extinguisher embodying my invention;

Fig. 2 is a cross section on the line 2, 2, in Fig. 1;

Fig. 3 is a sectional detail of part of Fig. 1, showing the handle partly drawn out of the casing, and

Fig. 4 is a side elevation of part of the extinguisher.

In the accompanying drawings the numeral 1 indicates a suitable casing adapted to contain a chemical liquid or solution, or analogous fire extinguishing material, to be forced from the casing for use. Within the casing is a cylinder 2, shown having heads 3, 4, at opposite ends. Said cylinder is shown supported at its inner end upon a discharge tube 5 extending within the casing and secured to the casing at its outer end, indicated at 6, as by solder, in any suitable manner. Within cylinder 2 and surrounding tube 6 is a tubular piston rod 7, shown having a cap 8 secured thereto at one end, the cap being provided with an aperture slidable upon tube 5. A handle is indicated at 9 secured to the outer end of piston tube 7, as by screw threads. Packing is indicated at 10 at the end of the casing around tube 7, and packing is shown at 11 within the handle 9 forming a tight joint around said tube. A piston is indicated at 12, slidably mounted upon tube 7 and adapted to have limited movement upon said tube between the head 8 and a stop 13 on said tube. Spaced apertures at 14, 15 in tube 7 admit liquid from the casing to said tube according to the position of piston 12. The spaced apertures 14, 15 are provided since the extinguisher illustrated is of the double-acting type. When handle 9 and tube 7 are pushed inwardly the piston will bear against stop 13 closing apertures 15 and opening apertures 14, and liquid will flow into tube 7 through apertures 14, and thence will flow through tube 5 and be discharged through orifice 5^a; when said handle and tube 7 are pulled outwardly, piston 12 will bear against head 8, closing apertures 14 and uncovering apertures 15, whereupon liquid will flow into tube 7 through apertures 15 and will be forced from tube 7 through its orifice 5^a. A valve indicated at 16 within the handle and pressed by a spring 17 closes the adjacent end of tube 5 when the handle is pushed to its normal position. A passage 17 communicates with a port 18 leading to cylinder 2 near one end thereof, and a passage 19 communicates with a port 20 leading to said cylinder near the opposite end thereof. Valves 21 and 22 respectively control the back flow through passages 17 and 19. Valves 23 and 24 are shown connected by a rod 25 that is movable in a passage 25^a,

which valves are adapted respectively to coact with seats 26, 27 in a well known manner. It will be noted that casing 1 is considerably longer than cylinder 2, and that tube 5
 5 extends within and through the casing beyond the inner end of cylinder 2, and discharges through the end of the casing opposite the handle. A tube 28 is shown secured in the tubular end of cap 4, and packing 29
 10 is located at the end of tube 28 to make a tight joint between the cap and tube 5. A cap 30 is secured at the outer end of tube 28 and is provided with an opening freely receiving tube 5, and the packing indicated at
 15 31 affords a tight fit between said cap and tube. By means of the packing 10, 29 and 31 the cylinder 2, tube 28, and parts connected therewith, may rotate upon tube 5, so that the valve devices may hang by gravity
 20 in different positions of the casing.

At 32 is a conduit or tube connected with cylinder 2 and communicating at its inner end with passages 17 and 25^a, the outer end of conduit 32 being shown located near the
 25 outer end of casing 1, the liquid receiving end 32^a of conduit or tube 32 being shown extended outwardly adjacent to the inner wall of casing 1. At 33 is a valve within conduit or tube 32, shown adjacent to its
 30 outer end, adapted to fit against a suitable seat 34 to retain the contents in said conduit or tube when the extinguisher is inclined downwardly, and to permit the flow into said conduit or tube of liquid or solution from
 35 casing 1. A stop at 33^a limits the inward suction of valve 33 in conduit 32. A brace or arm 35 is shown connecting conduit or tube 32 with tube 28, whereby the outer end of the conduit or tube 32 is supported and said
 40 conduit or tube will hang by gravity from cylinder 2 and tube 28 in different positions of casing 1.

The casing may be charged through an opening provided with a closure at 36. The
 45 handle 9 may be kept closed upon the casing by any suitable means, such as the bayonet joint indicated at 37, 38, in a well known manner, whereby when the extinguisher is to be operated, the handle may be turned in
 50 one direction, as to the left, to release it from the casing, and when the handle is to be locked in place it may be turned to the right, in a well known manner.

By the means described, the operating
 55 parts of the extinguisher, such as the slideable tube 7 and the cylinder 2, may be made relatively short, so that by means of relatively short strokes of the handle and piston the operator may cause the discharge,
 60 through tube 5 and from orifice 5^a, of the

contents of the casing, and yet the casing may be made considerably longer than the operating parts, so as to contain a relatively large volume of extinguishing material or liquid. The extension of conduit or tube 32
 65 from cylinder 2 to a point within the casing adjacent to the outer end of the latter, enables the liquid or extinguishing material to be drawn into cylinder 2 from the outer end of the casing when the extinguisher is inclined downwardly from the handle to discharge substantially all of the contents of the extinguisher. It will be understood, of course, that when the extinguisher is inclined downwardly the liquid will be directed through 70 conduit or tube 32 both to the valve 21 and to valve 22 to cylinder 2, and that if the extinguisher be inclined upwardly the contents will be directed through valve 22 and also through valve 21, to the cylinder 2, and 80 thence through tube 7 to tube 5 and from its orifice 5^a.

Having now described my invention what I claim is:

A fire extinguisher comprising a casing, a 85 discharge tube extending longitudinally within the casing and having a delivery orifice at one end of the casing, pumping mechanism within the casing comprising a cylinder rotatively mounted upon the discharge 90 tube and having valved inlet passages adjacent the opposite ends communicating with the casing, a piston within said cylinder, and means to operate the piston, said casing being longer than said cylinder, the latter being 95 located within the casing at the end thereof opposite the discharge orifice, a conduit within the casing communicating at one end with the aforesaid passages and extending within the casing beyond the cylinder to 100 a point adjacent to the outer end of the casing, a tube connected with said cylinder between the latter and the outer end of the casing and rotatively mounted upon the discharge tube to rotate with the cylinder, and 105 a brace connecting said rotative tube with said conduit whereby the cylinder, conduit and last named tube are rotative together relatively to the casing to permit the conduit to receive fluid from the end of the casing 110 distant from said cylinder when the casing is tilted downwardly toward the discharge orifice.

Signed at New York city, in the county of New York, and State of New York, this 25th day of October, A. D. 1916.

ROCCO VERDONE.

Witness:

MARIE F. WAINWRIGHT.
